Primary Examiner — Ricky Pham(74) *Attorney, Agent, or Firm* — David J. Wilson**CLAIM**

The ornamental design for novelty utensil, as shown and described.

DESCRIPTION

FIG. 1 is a side view of the novelty utensil. Both sides are mirror images and only one side is shown.

FIG. 2 is a front view of the novelty utensil.

FIG. 3 is a rear view of the novelty utensil.

FIG. 4 is a top view of the novelty utensil.

FIG. 5 is a bottom view of the novelty utensil; and,

FIG. 6 is a perspective view of the novelty utensil.

The broken lines shown in the drawings are for illustrative purposes only and form no part of the claimed design.
